UNITED STATES PATENT OFFICE.

JOHN D. MORITZ, OF REMSEN, IOWA.

END-GATE FASTENER.

1,246,141.

Specification of Letters Patent. Patented Nov. 13, 1917.

Application filed June 16, 1917. Serial No. 175,156.

To all whom it may concern:

Be it known that I, JOHN D. MORITZ, a citizen of the United States, residing at Remsen, in the county of Plymouth, State 5 of Iowa, have invented certain new and useful Improvements in End-Gate Fasteners; and I do hereby declare the following to be a full, clear, and exact description of the invention, such as will enable others skilled 10 in the art to which it appertains to make and use the same.

This invention relates to improvements in end gates and particularly to fastening means therefor.

15 One object of the present invention is to provide a novel and efficient device of this character whereby the end gate will be firmly held in proper closed position.

20 Another object is to provide a device of this character whereby the sides of the wagon box will be effectively clamped together to hold the gate.

25 Another object is to provide novel means for supporting the gate holding means against dropping down or being disarranged when not in use.

30 Other objects and advantages will be apparent from the following description when taken in connection with the accompanying drawing.

In the drawing:

35 Figure 1 is a rear elevation of the end gate and portion of the wagon showing my improved fastening means in closed position.

Fig. 2 is a side elevation of the same.

Fig. 3 is a top plan view of the same.

Fig. 4 is a top plan view of the device showing the same in disengaged position.

40 Fig. 5 is a transverse sectional view taken on the line 5—5 of Fig. 1.

Referring particularly to the accompanying drawing 10 represents the side boards of the wagon, having the cleats 11 for the 45 reception of the end gate 12 therebetween, and the bottom represented at 13. Secured to the outer face of each of the side boards is a plate 14, the rear end of which projects beyond the rear end of the side board. This 50 projecting end of the plate is formed with a pair of vertically alined slots 15, the portions of the plate, at the outer sides of said slots being rolled into tubular form, as shown at 16.

A pair of elongated strips 17 each has one 55 end formed with an enlarged portion 18,

said portion being formed with a pair of tongues 19 which are engaged through the said slots, and then curved to retain them in said slots, thereby forming a hinge. In the enlarged portion of each of the strips 60 17 there is formed a vertical slot 20. The inner ends of the strips 17 are adapted to meet in overlapping relation and are formed with horizontal alining slots 21 for the reception of the staple 22 carried by the intermediate portion of the outer face of the end gate. A pin 23, connected to the gate by means of a short length of chain 24, is adapted to be passed through the staple, after the strips 17 have been engaged therewith, to hold the parts in proper engagement with the gate and the gate against disengagement from its position between the cleats and the side boards of the wagon. 65

Secured to the end gate, adjacent the ends 70 thereof, are the plates 25, each of which is formed with an outwardly extending lug 26 for reception in one of the slots 20 of a strip 17. These lugs, by their engagement with the strips or hasps 17, hold the said hasps 75 in proper position with respect to the sides of the wagon and insure their proper relation to each other and to the staple of the end gate when they are to be engaged with said staple. While I have referred to the 80 member 22 as a staple, a reference to the drawing will show that said member is more properly an eye-bolt, although a staple may be as readily used.

It will thus be seen that I have provided a 90 novel and simple, as well as a cheap device for attachment to a wagon for the purpose of holding the end gate in proper position, while at the same time drawing together and holding the side boards of the wagon. 95

On the sides of the wagon, forwardly of the end gate, there are mounted the turn-buttons 27 which are adapted to be engaged in the slots 21 of the strips 17 when said strips are swung around against the sides 100 of the wagon to hold them out of the way.

What is claimed is:

The combination with the sideboards and end gate of a wagon, of plates secured to the rear end portions of the side boards, said 105 plates being formed with slots, elongated strips having tongues on their inner ends and engaged through the said slots to form hinged connection with the plates, said strips having slots adjacent their hinged 110

ends, a loop member carried by the end gate, the outer ends of the strips being formed with slots for the reception of said loop member, and plates secured to the end portions of the gate and formed with outwardly projecting lugs for engagement through the first-named slots of the strips.

In testimony whereof, I affix my signature in the presence of two witnesses.

JOHN D. MORITZ.

Witnesses:

F. A. SIEVERS,
C. J. AHMANN.
